DESIGN FOR A STOOL

Lurelle Guild, Darien, Conn., assignor to The Aluminum Cooking Utensil Company, New
Kensington, Pa., a corporation of Pennsylvania

Application November 13, 1945, Serial No. 123,682

Term of patent 14 years

(Cl. D15—8)

To all whom it may concern:

Be it known that I, Lurelle Guild, a citizen of the United States, residing at Darien, in the county of Fairfield and State of Connecticut, have invented a new, original, and ornamental Design for a Stool, of which the following is a specification, reference being had to the accompanying drawing, forming a part thereof, in which:

Fig. 1 is a top plan view;
Fig. 2 is a front elevational view; and
Fig. 3 is a side elevational view of a stool embodying my new design.

I claim:

The ornamental design for a stool, substantially as shown.

LURELLE GUILD.
